UNITED STATES PATENT OFFICE.

EDNA T. RASMUSSEN, OF LOS ANGELES, CALIFORNIA

VANITY CANE.

Application filed May 28, 1925. Serial No. 33,519.

To all whom it may concern:

Be it known that I, EDNA T. RASMUSSEN, a citizen of the United States, and resident of Los Angeles, Los Angeles County, State 5 of California, have invented new and useful Improvements in a Vanity Cane, of which the following is a specification.

This invention relates to canes and especially to ladies' walking canes.

10 An object of the invention is to provide a cane having a hollow head providing a number of chambers for toilet or compact supplies and for containing smokers' supplies.

An object is to provide a magazine in the 15 head and to provide means for shifting the magazine so as to project a portion of the length of cigarettes beyond the head when a cover thereon has been opened. And an object is to provide a match drawer operatively 20 connected to the magazine so that as the latter is actuated, the drawer will open and present matches.

An object is to provide means to operate the magazine to present cigarettes and provide for retraction of the magazine by finger pressure upon the open drawer.

Another object is to provide for low cost of manufacture by reason of simple design of the several parts, and a ready mode for 30 the assembly thereof.

It seems a growing fashion of the day for the feminine to indulge in the smoking of tobacco, and especially cigarettes, and since ladies' afternoon and evening dresses are 35 not provided with pockets and since at afternoon affairs vanity cases cannot be well carried around and, as the carrying of a cane is modish, I aim to provide an article which will be at once ornamental and useful as a container for compact supplies and smokers' requirements, and will not be of a conspicuous but of a "smart" character.

With these, other objects and advantages 45 will be made manifest in the following specification of apparatus of one embodiment of the invention; modifications, variations and adaptations being deemed within the scope of the invention as it is here claimed.

50 Figure 1 is a perspective of the cane, showing it tilted over from a vertical position (in dotted lines).

Figure 2 is a perspective showing the vanity pockets open.

55 Figure 3 is a vertical section showing the magazine in cigarette projecting position.

Figure 4 is a sectional and elevational view at a right angle to that of Figure 3.

Figure 5 is a perspective of the crank-pin.

Figure 6 is a plan of one section of the 60 crank shaft.

The cane 2 has a suitably shaped head 3, here of square box form, and having a hinged lid 4 which, preferably, is provided with a miniature bust 5 having natural hair 6, which will be that of the owner of the cane or a near resemblance thereto.

The box head 3 has a lower main part 70 fixed on the cane 2, and an upper section 7 with a top tray 8 for a powder puff coverable by the lid 4.

The upper section 7 is hinged at 8' to the box 3 and has a flap 9 to close over the near mouths of small pockets 10, 11, 12 for rouge, lip-stick and perfume bottle.

75 The top section 7 form a closure for the box 2 and has any suitable snap fastener 13.

Telescoping easily in the box 2 is a magazine 15, shorter than an ordinary cigarette C.

In the bottom of the box 2 is a drawer 16 80 for matches M which are pressed toward the top of the drawer by a leaf spring 17.

A ledge 18 in the box 2 holds the matches in the drawer when this is inside.

Means are provided for lifting the magazine 85 from retracted position to an upper position so as to expose the cigarettes partly beyond the box mouth so that one may be readily grasped without picking into the box or magazine.

90 Means are provided to extend the drawer 16 from its side of the box. Preferably the magazine actuating means and the drawer actuating means are combined for simultaneous action. Also, I provide means whereby, when the drawer is repressed by hand, the magazine is retracted.

95 The operating means includes a crank-shaft formed of duplicate sections 20 having diametrical facets 21 to be overlapped and 100 having tapped holes 22 to be aligned to receive the threaded end of a crank-pin.

105 Each shaft section has a button head 24 and is laterally recessed on opposite sides at 25 to form a flat neck 26 which is designed to interlock in a segment of a gear 28 which meshes with a rack portion 29 provided in the drawer 16, as by perforating its bottom. The center of the segment is slotted to fit snugly on the neck 26 of the 110 crank-shaft section.

Opposite side walls of the box 2 are perfo-

rated to receive and bear the inserted shaft parts and these are overlapped at their ends 21, and a pin 30, having a T-head 31, is passed down through the bottom of the 5 magazine; the bottom having a pair of down drawn rails 32 spaced to receive the pin 30 whose head is longer than the width of the pair of rails. The lower end of the pin is threaded at 30^a to screw into the 10 crank-shaft holes 22 and thereby hold these together as a unit with which the pin is rigid so that as the shaft rotates the pin-head 31 (set across the rails 32) will raise or lower the magazine.

15 The length of the rails 32 allows sweep of the pin-head and in the upper position of the magazine the pin-head passes over the crank center and resting on a near end shoulder 32^a of the rails, prevents the accidental retracting movement of the magazine.

20 When assembled, the buttons 24 lie close to the sides of the box and form ornaments as well as being finger grips whereby to turn or hold the crank-shaft.

25 When the cover section 7 has been opened to uncover the cigarettes, the magazine will be raised by a relative rotation of the crank-shaft and the box 2. This is accomplished by gripping the buttons between the thumb and a finger and rotating the buttons.

30 To be "smart" it is only necessary to grip the buttons and freely suspend the cane thereby and then deftly pull the head of the cane with a movement perpendicular to the 35 axis of the shaft. In this action the inertia of the lower end of the cane will cause it to rock on the crank shaft and to cause the magazine to rise. The same result will be secured if the buttons are gripped 40 and the cane is dropped from a horizontal to a vertical position.

45 Finger pressure against the extended drawer will cause it to move in and rock the shaft 20 and thereby pull down the magazine.

What is claimed is:

1. A cane box head, a movable cover for the head, and a magazine fitting in the box and movable to extend objects therein 50 at the top of the head when the cover is opened and means for retracting the magazine.
2. A cane head, a magazine sliding in the head, and means for moving the magazine in and out.

3. A cane head, a magazine sliding in the head, and means for moving the magazine in and out; said means including a crank-shaft having finger buttons lying against the opposite walls of the head.

4. A hollow staff head, a magazine sliding in the head, and means for moving the magazine in and out; said means including a crank-shaft having finger buttons lying against the opposite walls of the head and 65 a crank-pin to pass dead center and lock the magazine in extended position.

5. A cane head, a magazine sliding in the head, means for moving the magazine in and out, and a drawer mounted in the head and 70 operatively connected to the magazine.

6. A cane head, a magazine sliding in the head, means for moving the magazine in and out, and a drawer mounted in the head and 75 operatively connected to the magazine; said drawer operative by and on its inward movement to retract the magazine.

7. A cane head, a magazine sliding in the head, means for moving the magazine in and out, and a drawer mounted in the head and 80 operatively connected to the magazine; said means including a crank-shaft having finger buttons lying against the opposite walls of the head.

8. A cane head, a magazine sliding in the head, and means for moving the magazine in and out; said means including a crank-shaft having finger buttons lying against the opposite walls of the head, the crank-shaft comprising two sections having overlapped 90 inner ends, and a crank-pin operating the magazine and securing the shaft sections together.

9. A cane head having a slidable magazine, a slidable drawer, and a crank-shaft 95 having a pin operating the magazine and being connected to the drawer to concurrently operate the drawer and the magazine.

10. A cane head having a slidable magazine, a slidable drawer, and a crank-shaft 100 having a pin operating the magazine and being connected by a gear member to the drawer.

11. A staff head comprising a container 105 having a slidable magazine with rails punched down from its bottom, and a crank pin having a T-head interlocked upon the rails.

EDNA T. RASMUSSEN.
